UNITED STATES PATENT OFFICE.

JOHN BULLOCK, OF BROOKLYN, AND LAURITZ U. LACOUR, OF LONG ISLAND CITY,
NEW YORK.

ELEVATOR SADDLE.

Application filed June 13, 1928. Serial No. 285,187.

This invention relates to elevator saddles, the part being sometimes referred to as a sill; an object of the invention being to provide a saddle composed of sections which may be securely coupled and so arranged as to provide any number of grooves for the guidance of elevator doors.

Heretofore in the art it has been the practice to cast or otherwise form the saddle or sill in a single piece, providing in the saddle the number of grooves necessary for the guidance of elevator doors. Some sills have a single groove, others two grooves, others three grooves, and of course a sill may have any number of grooves; and it is the purpose of my invention to provide a series of members with the employment of which a saddle or sill may be provided having a desired number of grooves.

With these and other objects in view, the invention consists in certain novel features of construction and combinations and arrangements of parts which will be more fully hereinafter described and pointed out in the claims.

In the accompanying drawings—

Figure 1 is a view in cross section through our improved sill having two grooves with fragments of elevator doors shown to indicate their mounting relative to the grooves of the sill;

Figure 2 is a broken perspective view showing our improved sill or saddle having a single groove;

Figure 3 is a view in transverse section through our improved saddle showing the parts arranged to form three grooves;

Figures 4, 5, 6 and 7 are fragmentary perspective views showing the different elements which go to make up our improved sill, these elements being employed in any desired number.

All sections or elements of our improved sill are preferably formed by extruding the metal, but of course the invention is not limited to any particular manner of forming the parts.

Our invention includes a plurality of different types or forms of strips, indicated in perspective in Figures 4, 5, 6 and 7, and given reference numerals 1, 2, 3 and 4, respectively. The strip 1 forms the nose or the front edge of the sill, the strip 4 forms the outer portion of the sill; and the strips 2 and 3 are forms of coupling strips connecting the strips 1 and 4

to provide the necessary grooves, as will be explained.

All of these strips are preferably grooved or otherwise surfaced to prevent slipping, and they may be of any suitable metal or other material.

The strip 1 has a depending flange 5 adjacent its front edge with a forwardly projecting bead 6 to give the proper finish to the edge of the elevator shaft.

The reference numeral 7 indicates an elevator, the reference numerals 8 and 9 indicating doors, or sections of the same door, but for purposes of description I shall refer to these parts as doors.

A downwardly projecting flange 10 is formed integrally on the strip 1, and an integral inwardly projecting flange 11 is provided at the lower edge of flange 10. A groove 12 is formed in the under face of the strip 1 above the flange 11 so that a longitudinally extending shoulder 13 is provided for a purpose which will hereinafter appear.

The section 2, which is a coupling section, has flanges 10 on its edges with inwardly projecting flanges 11 thereon and grooves 12 with shoulders 13. We employ the same reference characters 10, 11, 12 and 13 to indicate like parts in each of the sections 1, 2, 3 and 4.

The section 3 has flanges 14 extending downwardly from an intermediate tread portion, and lateral extensions 15 are formed integral with the lower portions of flanges 14. Flanges 10 extend at right angles to the extension 15 and have integral, inwardly projecting flanges 11 thereon, and grooves 12 are provided in the extensions 15 forming shoulders 13, as clearly indicated in Figure 4.

The section 4 has at one edge an integral flange 10 with an integral, inwardly projecting flange 11 thereon and is provided with a recess or groove 12 forming the shoulder 13, as clearly indicated in Figure 7. The outer edge of section 4 is preferably formed with a flange 16 extending at right angles thereto.

In forming the saddle or sill with a single groove for the reception of a guide pin or other device 17 on the elevator door, we utilize sections 1, 2 and 4, as shown in Figure 2. These sections are securely coupled by positioning the inwardly projecting flanges 11 of the three members in coupled relationship, that is, the flanges 11 of member 2 are positioned over the flanges 11 of members 1 and 4, with said flanges 11 of the respective

members fitting in the grooves 12 of each other.

The parts must be put together by a longitudinal movement, and the shoulders 13 of 5 the respective members prevent any possibility of lateral displacement. When the members 1 and 4 are thus coupled by the member 2 the edges of members 1 and 4 are spaced apart forming the groove for the 10 elevator door pin.

When a two-groove sill or saddle is desired the section 3 is used in place of the section 2, and said sections 1, 3 and 4 are coupled by 15 the same arrangement of flanges and grooves, as clearly indicated in Figure 1 of the drawings.

Where a three-groove construction is desired it is necessary to employ two sections 2 in addition to the sections 1, 3 and 4, as 20 clearly indicated in Figure 3 of the drawings.

In the formation of a sill or saddle having any desired number of grooves the sections are always coupled by the same arrangement of flanges and grooves and are joined by 25 means of one part relative to the other, and there can be no lateral displacement after the parts are once coupled.

It is this broad idea of the arrangement of 30 tongue and groove members whereby a plurality of sections may be utilized to form sills or saddles having any desired number of

grooves that constitutes the broad idea of our invention, and we do not wish to be limited to specific details of construction but desire to cover the idea broadly as expressed 35 in the appended claims.

We claim:

1. As a new article of manufacture, an elevator saddle composed of a plurality of sections having interlocking engagement, said 40 interlocking engagement consisting of inwardly projecting flanges on the respective sections, and grooves in the respective sections receiving the overlapping flanges of the 45 sections.

2. An elevator sill or saddle composed of a plurality of sections, and coupling means connecting the sections and spacing them to form a groove.

3. An elevator sill or saddle comprising a 50 plurality of standard sections having tongue and groove interlocking engagement, said sections coupled in any desired way to form any desired number of grooves in the sill or saddle.

4. A sill or saddle comprising a plurality of interlocking longitudinal sections, all of 55 said sections of general channel shape having inwardly projecting flanges, and grooves receiving the flanges.

JOHN BULLOCK.
LAURITZ U. LACOUR.
